(57) **CLAIM**

The ornamental design for an electric bicycle, as shown and described.

DESCRIPTION

FIG. 1 is a top, front and right-side perspective view of an electric bicycle showing my new design;

FIG. 2 is a right-side elevation view thereof;

FIG. 3 is a left-side elevation view thereof;

FIG. 4 is a rear elevation view thereof;

FIG. 5 is a front elevation view thereof;

FIG. 6 is a top plan view thereof;

FIG. 7 is a bottom plan view thereof;

FIG. 8 is a bottom, rear and left-side perspective view thereof;

FIG. 9 is an enlarged view of the portion 9 in FIG. 4; and, FIG. 10 is an enlarged view of the portion 10 in FIG. 4.

The broken lines depict portions of the electric bicycle that form no part of the claimed design.

The dot-dash lines on FIGS. 4 and 9-10 define the bounds of the enlarged portions of FIG. 4 and form no part of the claimed design.

1 Claim, 10 Drawing Sheets
